UNITED STATES PATENT OFFICE.

WILBUR L. WRIGHT, OF FULTON, NEW YORK, ASSIGNOR TO OSWEGO FALLS CORPORATION, OF FULTON, NEW YORK, A CORPORATION OF NEW YORK.

EXTERIORLY CAPPING CONTAINERS.

Application filed July 23, 1923. Serial No. 653,196.

To all whom it may concern:

Be it known that I, WILBUR L. WRIGHT, a citizen of the United States of America, and resident of Fulton, county of Oswego, State of New York, have invented certain new and useful Improvements in and Relating to Exteriorly Capping Containers, of which the following is a specification.

This invention relates to fibrous such as paper or paper material cover all or hood caps for bottles and other containers; and the objects and nature of the invention will be readily understood by those skilled in the art in the light of the following explanations of the accompanying drawings that illustrate what I now believe to be the preferred mechanical expression or embodiment of my invention from among other forms, constructions, arrangements or combinations within the spirit and scope thereof.

An object of the invention is to provide a fibrous material hood or skirted cap with a series of applied means for positively holding the cap skirt or flange contracted under the bottle or container rim and the cap thereby normally confined on the bottle mouth, and particularly such means that are necessarily removed with the cap and that will not remain on the bottle neck after removal of the cap for subsequent removal by the bottler.

With this and other objects in view, my invention consists in certain novel features of construction, arrangement, or combination, as more fully and particularly set forth and specified hereinafter.

Referring to the accompanying drawings forming a part hereof:

Fig. 1 is a perspective of the mouth portion of a container exteriorly capped in accordance with my invention.

Fig. 2 is a side elevation of the showing of Fig. 1.

Fig. 3 is a top elevation of the disclosure of Fig. 2.

In the drawings, I show any container, such as bottle 1, having its mouth surrounded by an exterior annular rim forming a downwardly facing shoulder.

I show the mouth of this bottle exteriorly covered and protected by a so-called hood or coverall cap composed of suitable usually comparatively inexpensive sheet fibrous material such as a suitable commercial paper.

This cap is usually imperforate and hooded, skirted or flanged to extend down onto the bottle neck and contract under the rim and to provide a usually flat round central top portion *a*, that spans and covers the top opening of the bottle and rests on the rim and which at its exposed top face is usually provided with printed or other advertising display matter, or other indicia.

The annular depending skirt or flange of the cap is of a length to extend down around and to a point below the exterior rim of the bottle mouth or neck and thus provide the depending securing portion capable of being contracted under said rim to secure and hold the cap on the bottle mouth.

A flat disk cut from sheet paper, is drawn or otherwise shaped by suitable dies or forming heads, to form the flanged or skirted cap. The skirted cap can be thus formed from the flat disk on the bottle mouth to be covered thereby, or the cap can be previously formed with a flaring flange or skirt, and thus applied over the bottle mouth so that the lower edge portion of the skirt can be contracted below the bottle rim with the surplus material taken up by the formation of tucks, pleats or folds.

In applying the cap to the bottle mouth, the forming head in contracting the cap skirt under the bottle rim or shoulder gathers the surplus material of the skirt, at intervals around the circle of the skirt, into vertical or longitudinal separate tucks, pleats, corrugations or folds 6, and render the same permanent by the application of exterior fasteners, binders or clips 5 compressed thereon. In the particular example illustrated, I happen to show six such pleats or outward folds 6, (but do not wish to so limit my invention) more or less uniformly spaced apart around the cap skirt, and I show separate clips or fasteners 5, one for each fold, arranged, transversely thereof and pinched thereon or otherwise, to tightly hold the opposite walls of pleats, tucks or folds together and against separation. In other words, the separate clamps, clips, or fasteners 5, permanently hold the folds compressed or collapsed and against expansion, and hence the securing portion of the cap skirt contracted under the bottle neck shoulder to secure the cap on the bottle mouth, against deformation or stretching under abnormal or adverse conditions.

105

110

These separate fasteners or clips are carried by and remove with the cap, and this is a feature of importance as the difficulty arising by reason of metal rings remaining on the bottle necks is thereby avoided. These encircling cap fastening metal bands and rings that remain on the bottle neck, constitute a source of expense, annoyance, and sometimes injury to the hands and fingers.

According to my invention, I form the hood skirt with several longitudinal spaced relatively-large vertical tucks or folds, arranged in a series around the circle of the skirt, each separately fastened by any suitable applied means, all removable with the cap, with these tucks or folds arranged to so take up the surface material of the skirt as to hold the skirt tightly contracted under the bottle mouth rim and thereby maintain the cap confined on the bottle mouth. The tightly compressed and fastened tucks or folds do not interfere with the tearing or loosening of the skirt preparatory to pulling the cap from the bottle mouth. In fact, if so desired, where the compressed tucks or folds project outwardly, as in the specific example illustrated (although I do not wish to so limit all features of my invention) any one of such projecting compressed tucks or folds may be grasped by the fingers for exerting on the skirt the force necessary to expand the same as by tearing or removal of a clip, so that the cap can be stripped, torn or otherwise removed from the bottle carrying the clips therewith.

In the particular example illustrated, the fasteners are in the form of U-shaped metal clips that are pinched on the tucks or folds to tightly compress the same, but I do not wish to so limit my invention, as the tucks or folds can be compressed and fastened by various individual fasteners.

These individual metal clips can be variously formed and can be applied to the cap by various means. For instance, the forming or gathering head that contracts the skirt of the paper cap to and around the bottle rim and neck, can take up the surplus paper of the skirt and form the several large tucks or folds and can be provided with means to then pinch the separate clips on such folds to maintain the same compressed and form a positive seal of the skirt under the bottle rim. It will be noted, of course, that any desired or suitable number of these

60 folds or tucks that are positively compressed or clipped, can be provided, notwithstanding the particular number and arrangement that I happen to show in the drawings for purposes of explanation.

Although I do not wish to so limit all features of my invention, it will be noted that the pinched-on clips of the particular example illustrated, can be individually stripped from the folds or pleats by the 65 fingers and hence, the cap can be released for removal by stripping off one or more of such clips.

Various changes, modifications and variations might be resorted to without departing 70 from the spirit and scope of my invention and hence I do not wish to limit my invention to the exact disclosures hereof.

What I claim is:—

1. A fibrous sheet material hood cap having 75 the surplus material of the contracted portion of its skirt forming spaced tucks or folds provided with individual fastening means compressing such folds and removable with the cap.

2. A sheet paper hood cap having its skirt formed with spaced tucks or folds held compressed by separate individual clips pinched thereon.

3. A hood cap having the securing portion 85 of its skirt gathered into relatively large longitudinal tucks each independently held compressed by individual applied fastening means.

4. A paper hood cap having portions of 90 its skirt gathered into folds, each fold being held compressed by a metal clip, a separate clip being provided for each fold, the clips being disconnected and removable with the cap.

5. A paper hood cap having its skirt formed with longitudinal folds or pleats and U-shaped metal clips pinched thereon compressing said folds against expansion.

6. A paper hood cap having its skirt 100 formed with spaced longitudinal pleats or folds each compressed and separately and individually fastened against expansion.

7. A paper hood cap having its skirt formed with pleats each secured against expansion by an individually removable clip.

In testimony whereof I have hereunto set my hand at Fulton, N. Y., this 19 day of July, 1923.

WILBUR L. WRIGHT.
